UNITED STATES PATENT OFFICE.

ALLERTON S. CUSHMAN, OF WASHINGTON, DISTRICT OF COLUMBIA.

METHOD OF PRODUCING COLOR EFFECTS.

1,423,089.

Specification of Letters Patent. Patented July 18, 1922.

Application filed June 10, 1921. Serial No. 476,595.

To all whom it may concern:

Be it known that I, ALLERTON S. CUSHMAN, a citizen of the United States, residing at Washington, in the District of Columbia, 5 have invented certain new and useful Improvements in Methods of Producing Color Effects, of which the following is a specification.

My invention relates to the art of producing color effects such as find more general application, for instance, upon the stage.

It is known that owing to the phenomenon of persistence of vision the human eye is capable of retaining a visual impression for 15 an appreciable time which will vary according to the intensity of the impression, the wave length of the light and the time involved in producing the impression. By taking advantage of this phenomenon and so 20 arranging and timing the succession of separate beams of differently colored light and the periods of occultation, I have discovered that I can produce new and useful effects when such beams of light are directed upon 25 moving objects.

It is the general object of the invention to provide a method of and a means for producing fascinating color effects.

For a full understanding of the invention 30 reference is had to the accompanying drawings in which—

Fig. 1 represents the general arrangement of a device for carrying out the object of the invention and an object acted upon;

35 Fig. 2 is a front view of a device embodying the invention on an enlarged scale; and Fig. 3 is a side view thereof.

In the drawings 1 represents a usual form 40 of projecting device for emitting a beam of light. In front of the projecting device is revolvably mounted a disk or wheel 2 driven by an electric motor 5. This disk carries a plurality of differently colored panes 3 separated by opaque portions 4. The arrangement is such that the colored panes and opaque portions pass successively past the aperture of the projecting device.

The object is for the purpose of illustration represented as a bundle of white 50 streamers 6 which under the influence of an agitating force of any kind, as for instance a fan 7, is fluttering in the path of the light beam.

When the disk 2 is revolved at a rate 55 which will be more particularly referred to, the individual streamers appear as com-

posed of a multitude of colored sections running transversely, longitudinally or obliquely of the individual streamers according to the general direction of the individual streamers 60 relatively to the light beam.

The total effect is a color riot of unusual beauty and numberless variations due principally to the irregularity of movement of the individual streamers. Every change of 65 position, every whimsical twist or turn of the different streamers introduces a new color variation.

While only one object has been mentioned for the purpose of explaining the principle 70 of operation, the number of objects to which the invention is applicable is without limit.

If, to cite another instance, a transparent receptacle containing water is shaken, the moving drops appear to flow with all manner of varying color.

An apparatus arranged under the general plan explained can be used for various purposes.

The principle on which the invention is 80 based is probably as follows:

Assume that the rate of rotation of the disk is such that the successive periods of light emission through each pane are too short to satisfy the law of persistency of 85 vision, a stationary or very slow moving object will appear in the color of the mixed light composed of the different light beams. Before the light due to one light beam has time to create a fixed impression on the retina and cause a definite color sensation corresponding to the wave length of the rays of that beam, the rays coming from the next beam and reflected from the object are superimposed upon the first etc. The light effect is that due to a more or less effective 90 blending of all the light rays.

A white object thus will appear as white so long as this condition is maintained, if the synthetic effect of the different beams is 100 substantially white light or it will appear in any other uniform color according to the particular synthetic effect of the various beams.

Since the disk 2 consists of alternate colored panes and opaque portions, each light beam is shifted in the direction of rotation of the disk. In the particular instance shown, as an opaque portion is just passing past the projecting aperture, the upper edge 105 of it will first uncover the aperture and then as it (the edge) passes downwardly, the 110

beam will be gradually allowed to pass until the edge has reached the lower limit of the effective aperture of the projecting device.

When the lower edge of the next opaque portion gradually shuts off the light from the top downwardly, the last rays of the beam are directed downwardly.

Thus the beam is in effect traveling through a substantially vertical angle and therefore 10 strikes the object first at the top and last at the bottom.

According to the relative positions of the projecting device and the disk 2, the apparent motion of the beam can of course be 15 changed as desired.

Assume now that the object or a part of the object has motion in the direction of the traveling beam and that its rate of motion corresponds to that of the beam. The object 20 or a part thereof, as the case may be, is thus under the illuminating effect of the light of a particular light beam during the whole period of duration of the beam. If this period is long enough to satisfy the law of 25 persistency of vision, the color or a part thereof will appear in the color of the beam.

If the same conditions are maintained for an appreciable length of time, the successive light beams will operate to change the color 30 of the object correspondingly.

Assume now that the rate of motion of the beam is greater than that of the object and that the relativity of motion is such that a plurality of differently colored light beams 35 will pass through their zones of action while the object or a part thereof passes through the same zone, the object or a part thereof, as the case may be, will appear in the colors of the plurality of beams, such colors being 40 juxtaposed much like the colors of the rainbow. This effect will take place only, however, if the time interval during which each color beam is allowed to act upon the object of the parts thereof satisfies the law of persistency of vision. 45

The limiting conditions of the invention thus are;

1. The differently colored light beams must follow each other at such rate that the 50 successive impulses are not sufficiently long to cause separate color sensations when the object is at rest.

2. The rate of projection must be such that during substantial motion of the object or 55 parts thereof light rays from the different beams persist long enough to cause color sensations corresponding to the respective beams.

3. Conversely the rate of projection must 60 not be so high that during the motion of the object no distinct and separate color sensation can be produced.

It is understood that the angular velocity 65 of the disk 2 or the angular ratio of the opaque portions and transparent portions, or

both may be varied to suit particular conditions as to the rate of motion of the object or its parts.

I have found that a speed of 200-1000 revolutions per minute of the disk gives satisfactory results with the usual moving objects. 70

The relativity of motion between the moving beams and the moving object may be varied within a considerable range satisfying 75 the law of persistency of vision and as a function of such variations the color effects produced upon the object or its parts vary correspondingly within wide limits.

The more separately moving parts the 80 object has and the more irregular and fantastic the movements of such parts are, the more grotesque and bizarre is the color effect and the greater is the range of variations.

In fact the number and character of the 85 different color effects is limited only by the creative faculty of the imagination.

In the foregoing reference has been made to a rotary disk. It is obvious, however, that a linear reciprocating movement or any 90 complex irregular movement will be equally or even more effective. There is, therefore, no limit in regard to the character of motion of the light beams.

There is likewise no limit in regard to the 95 color values of the panes employed nor to the form of the individual panes nor to the number of the panes on a disk nor to the relation of angular extent of the panes and opaque portions or any of them, so long as 100 the device is susceptible of manipulation to bring about color effects such as referred to.

In reality the invention can be carried out in various other ways. A disk composed of alternate opaque and transparent colored 105 portions has been referred to merely as a simple arrangement.

The periodical occultations essential for producing the light effects described may be carried out by means of the various 110 forms of shutters well known in connection with the motion picture art. In the light of the general knowledge in this respect it is unnecessary to illustrate shutter mechanisms for controlling the emission of differently colored light beams. Within the scope of this invention color screens containing a plurality of differently colored sections may be moved in front of the projecting device and the syncopations may be effected by a 115 120 shutter mechanism of any known type.

Within the scope of the invention a plurality of sources of differently colored light may be separately controlled by means of shutters so that beams of differently colored 125 light may be intermittently projected upon the object, the time relation of the periods of projection and the periods of occultation bearing of course the same relation to each other as those pointed out above. 130

While it is thought that the theory above discussed is a true explanation of the phenomena described, it is by no means insisted that it is correct or complete.

5 In the claims the expression "loosely cohering" is intended to include all objects of which parts are freely movable with respect to one another.

I claim.

10 1. A method of producing color effects which consists in projecting successively and intermittently separate beams of differently colored light upon a moving object at such a rate of succession that different parts of the 15 moving object exhibit different color effects, the rate being at the same time such that the light effect produced upon a stationary object is a uniformly blended color.

2. A method of producing color effects 20 which consists in projecting successively and

intermittently separate beams of differently colored light upon a moving object having a large number of independently moving parts, at such rate of succession that the different parts exhibit separate and distinctive color effects.

3. A method of producing color effects which consists in setting an object having loosely cohering parts into a state of agitation and successively and intermittently projecting separate beams of differently colored light upon said object, the rate of succession being so rapid that when the object is at rest a uniform blended color is produced, and that when the object is agitated different 35 distinct color effects are produced.

In testimony whereof, I affix my signature.

ALLERTON S. CUSHMAN.
